UNITED STATES PATENT OFFICE.

THOMAS DANQUARD, OF NEW YORK, N. Y., ASSIGNOR TO AUTO PNEUMATIC ACTION COMPANY, A CORPORATION OF NEW YORK.

SWITCHING MECHANISM FOR PLAYER PIANOS.

Application filed March 31, 1920. Serial No. 370,150.

To all whom it may concern:

Be it known that I, THOMAS DANQUARD, a citizen of the United States, residing at New York, in the county of New York and 5 State of New York, have invented a new and useful Switching Mechanism for Player Pianos, of which the following is a specification.

This invention relates to a switching mechanism particularly designed for use in 10 player pianos.

It is now common to equip player pianos with especial expression or accenting devices controlled from tracker openings. As the 15 number of available tracker openings is limited, it is also common to steal a few of the regular note openings to control parts of the accenting or expression mechanism. Specially cut music is always required with 20 such expression or accenting devices.

It frequently happens that the operator of the instrument desires to use regular eighty-eight note music in the same instrument, and it is then desirable to use all of 25 the eighty-eight notes of the standard player piano. It is one object of my invention to provide improved mechanism for switching the tracker openings from one set of connections to another, so that either style of 30 music may be used.

It is also sometimes desirable to use a certain special device, such as a reroll mechanism, with both kinds of music, but to control said device from different tracker-openings. It is another object of my invention to 35 provide means for thus connecting a single device to either one of two tracker openings.

Further objects of my invention relate to certain arrangements and combinations of 40 parts which will be hereinafter described and more particularly pointed out in the appended claims.

A preferred form of my invention is shown in the drawings, in which—

45 Fig. 1 is a front elevation of a portion of a music-box, with my switching mechanism mounted thereon;

Fig. 2 is a partial plan view of the switching mechanism;

50 Fig. 3 is a side elevation of the manually controlled switch lever;

Fig. 4 is a plan view of the switch base, with one valve block in position;

Figs. 5 and 6 are partial sectional front

elevations, taken along the lines 5—5 and 55 6—6 in Fig. 4;

Fig. 7 is a transverse sectional elevation taken along the line 7—7 in Fig. 5;

Fig. 8 is a bottom view of one of the valve-blocks, and

Figs. 9 and 10 are detail plan views, showing the connections made by the block shown in Fig. 8.

Referring to the drawings, I have shown a music or spool-box 20 having a tracker bar 65 21, and supporting the usual music roll 22 and note-sheet 23. My improved switching mechanism is preferably mounted on the top of the music box 20 and comprises a base 24, a plurality of valve-blocks 25 (Fig. 79 5), and a bar 26 mounted to slide between guides 27 and longitudinally of the base 24. A screw 28 extending through a slot 29 in a plate 30 and threaded in to the bar 26 limits longitudinal movement thereof in both 75 directions.

The bar 26 is connected by a link 31 to a bell-crank 32, mounted upon a fixed pivot 33 and connected by a link 34 to an arm 35 secured to a short shaft 36. The shaft 36 extends through the side of the music box 20 and is provided with an arm or handle 37 at its inner end, projecting forward over an index plate 38, (Fig. 3). Stop-pins 39 limit the movement of the handle in both directions. The switching mechanism is operated by the handle 37 to render the expression mechanism operative or inoperative as desired.

The base 24 is divided into several sections, each controlled by a single valve-block 25, and having from two to six openings in its upper face, suitably connected to tracker openings or to devices to be controlled from the tracker.

The most complete arrangement is shown at A in Fig. 4, at which point there are two sets of three passages each, having their open ends in parallel rows. The middle passages 40 and 41 are each connected to corresponding tracker openings. The left hand passages 42 and 43 may be connected to the usual player actions, and the right hand passages 44 and 45 will be correspondingly connected to special expression devices.

The corresponding valve-block 25 is shown in Figs. 5 and 6 in its right hand position, connecting the passage 40 from a tracker

opening, through the valve-block and the passage 44 to one of the expression devices, and at the same time connecting the passage 41 from another tracker opening through the valve-block and the passage 45 to another expression device.

If the valve-block 25 is now moved to its left-hand position, the passage 40 will be connected to the passage 42 and the passage 41 will be connected to the passage 43, thus rendering operable the two regular note playing actions connected thereto.

It is sometimes desirable to connect a single special device, such as a re-roll mechanism, for use with either type of note sheet, but to control said device from a different tracker opening with each note sheet.

For this purpose I arrange the base section B (Fig. 4) and provide the valve block 25^a shown in Figs. 8 to 10, having the usual air passages 46 and 47, as in the block 25 previously described, and having also an additional, diagonally-disposed passage 48 connecting a port 49 with the passage 47.

The connections for this valve block are shown in Figs. 9 and 10, in which 50 and 51 indicate passages connected to tracker openings, 52 is a passage connected to one of the usual note playing actions, and 53 and 54 are passages connected to special devices. Let it be further assumed that the passage 53 is connected to a re-roll mechanism or to some other device to be used with both types of note sheets.

If the expression mechanism is to be used, the valve block 25^a is shifted to the position shown in Fig. 9, in which the passage 53 from the re-roll mechanism is connected through the valve block and the passage 50 to one tracker bar opening, while the passage 54 at the same time connects an expression device to another tracker opening through the valve-block and the passage 51.

If regular music is to be played, the valve block 25^a will be shifted to the position shown in Fig. 10, in which one of the regular player actions is connected through the passages 52 and 50 to the tracker bar, and in which the re-roll or other mechanism is connected through the passage 53, port 49, diagonal passage 48 and passage 51 to the tracker bar.

It will thus appear that the re-roll mechanism is operably connected with the tracker bar in both positions of the valve-block 25^a, but is connected to a different tracker opening in each position of the block.

Each valve-block is preferably provided

with pins 55 extending upward into holes in the under side of the bar 26, and also with a lug 56 positioning a spring 57 extending upward into an additional opening in the under side of the bar 26. The pins 55 accurately position the valve block and the spring 57 holds the same firmly seated against the base 24.

It will be noted from Fig. 4 that the passages in the base 24 are variously grouped and arranged as may be found desirable in actual practice.

Having thus described my invention and one embodiment thereof, it will be evident that changes and modifications can be made therein by those skilled in the art, within the spirit and scope of my invention as set forth in the claims, and I do not wish to be otherwise limited to the details herein disclosed, but what I claim is:—

1. In a piano-player a plurality of tracker controlled devices, and a switching mechanism comprising means effective to connect one of said devices to either one of two different tracker openings, and two additional devices by the same operating means alternately to a single tracker opening.

2. A switching mechanism for a player-piano comprising a base, connections from said base to a plurality of tracker openings, additional connections from said base to a plurality of tracker controlled devices, a plurality of valve blocks slidable on said base, and manual means to move said blocks simultaneously to either one of two operative positions, said blocks having longitudinally extended air passages therein, and one of said blocks having an additional diagonal passage whereby one device may be connected to either of two different tracker openings.

3. A switching mechanism for a player piano comprising a base having openings in its face, a plurality of valve blocks mounted on said base and having air passages therein, a cap for said base having a longitudinal guide-way therein, a bar mounted to slide in said guide-way over said blocks, said blocks and bar having co-operating pins and holes to relatively position said blocks, separate springs interposed between said bar and said blocks to independently seat each block on said base, and manual means to slide said bar, moving said blocks simultaneously on said base.

In testimony whereof I have hereunto affixed my signature.

THOMAS DANQUARD.
